UNITED STATES PATENT OFFICE.

JOHN F. TOOMEY, OF NEW YORK, N. Y., ASSIGNOR TO AMERICAN TELEPHONE AND TELEGRAPH COMPANY, A CORPORATION OF NEW YORK.

SUBSCRIBER'S EQUIPMENT FOR PROGRAM TRANSMISSION.

Application filed December 1, 1923. Serial No. 677,993.

This invention relates to program transmission over wires and particularly to systems in which a program channel, employing audio frequencies, is superposed upon an ordinary subscriber's telephone line.

It has been proposed to use ordinary subscribers' telephone lines for program purposes by transmitting program currents over the lines at voice frequencies during such times as the telephone line is not being used for ordinary telephonic purposes. Under such circumstances it is desirable that the program system be so superposed on the telephone line that the program apparatus will be disconnected either when a call comes in to the subscriber's line or when the subscriber desires to send out a call.

It is one of the objects of the present invention to so arrange the subscriber's apparatus that a low impedance loud speaker may be used at the subscriber's station for program purposes and may be disconnected automatically as soon as the operator plugs into the subscriber's line. The disconnection actually takes place before the line is disconnected from the program equipment at the central station and connected to the calling jacks. Another object of the invention is to so arrange the subscriber's circuit that the loud speaker will be disconnected at once upon taking the receiver from the switchhook of the telephone set.

Another object of the invention is to prevent the low impedance program receiving set from actuating the central office line equipment. It has heretofore been proposed to accomplish this result by including a condenser in circuit with the program receiver. As the use of such a condenser produces some distortion in the program transmission, which is highly undesirable, particularly in the transmission of music, it is proposed in accordance with the present invention to accomplish this result by operating the line signal equipment at the central office over a simplex circuit. Since the subscriber's receiving equipment is bridged across the line it will not produce any effect upon the simplex circuit.

Other and further objects of the invention will be clear from the following description when read in connection with the accompanying drawing, the figure of which illustrates a circuit arrangement embodying a preferred form of the invention.

Referring to the drawing, L designates a subscriber's line terminating in the usual subscriber's set 10. At the central office the line is connected over the back contacts of the cut-off relay CO and through a transformer 11 to a trunk T leading to a program station. A jack J is provided for establishing connections to the telephone line L through the central office in the usual manner and a line lamp 12 is connected from the midpoint of the secondary of the transformer 11 to battery over a back contact of the jack J. The front contact of said jack is connected to the cut-off relay CO.

At the subscriber's station a low impedance loud speaker 13 is provided, this loud speaker being associated through a transformer 19 with a bridge circuit 17, through which the loud speaker is connected to the line. The bridge circuit is controlled by the contact of a high resistance relay R, which is connected over conductor 20 and the contact of a relay 21 to the midpoint of the primary of the transformer 19. A non-locking key K is provided, whose contacts 15 and 16 control the circuit from the relay R to ground. A direct circuit to ground, independent of the relay, may be established over the contact 14 of the subscriber's switchhook.

The operation is as follows: When a subscriber desires to make an ordinary telephone call he takes the receiver from the switchhook, thereby closing a connection from ground, over the contact 14, over conductor 20, back contact of relay 21, through the upper half of the primary winding of the transformer 19 and thence in parallel over the tip side of the line L, and through the subscriber's set over the ring side of the line L, thence over the back contacts of the cut-off relay CO through the upper and lower halves of the primary winding of the transformer 11 to the midpoint thereof and from this point through the line lamp 12 over the back contact of the jack J to battery. The line lamp now glows and notifies the operator that a connection is desired. The operator thereupon plugs into the jack J and disconnects battery from the line lamp 12, extinguishing the latter. At the same time, battery is connected to the winding of the cut-off relay CO and upon the energization of the latter the line L is disconnected from the trunk T and con-

nected to the tip and ring terminals of the jack J. The battery supply is now furnished to the line L over the tip and ring conductors of the jack J and the relay 21 is 5 energized to open the connection 20 so that the usual metallic telephone connection, independent of any grounds, is established.

If the subscriber desires to receive program transmission the non-locking key is actuated to momentarily close the contact 15 so that a circuit is established from ground, over the contact 16, contact 15, through the winding of the high resistance relay R, over the back contact of relay 21, over the upper 15 half of the primary winding of the transformer 19, over the tip side of the line, back contact of cut-off relay CO through the upper half of the primary winding of transformer 11 through the line lamp 12 and over the back contact of the jack J to battery. Owing to the high resistance of the relay R the line lamp 12 is not caused to glow but the relay R is energized and locked up over its front right-hand contact, independently of the contact 15. At its left-hand contact the relay R completes the bridge circuit 17 through the primary of the transformer 19 so that the loud speaking receiver 13 is now bridged across the line L. While the resistance of the circuit, including the relay R and the line lamp L, is now somewhat reduced owing to the completion of a parallel circuit over the ring side of the line at the time the relay R was 35 energized, the resistance is not sufficiently reduced to permit the lamp 12 to glow, as the resistance of the relay R is quite high as compared with the resistance of the line. Program transmission may now be received 40 from the program station through the transformer 11 and over the metallic line circuit through the transformer 19 to the loud speaker 13. The fact that the loud speaker is of low impedance has no effect to operate 45 the line lamp as the loud speaker is included in the circuit over the two sides of the line in series where the line lamp is included in a circuit over the two sides of the line in parallel.

If, while the subscriber's line is being used for program transmission, a call should come in for the subscriber the operator will 50 insert the plug of her cord into the jack J, thereby disconnecting battery from the circuit through the line lamp 12 and over the two sides of the line L in parallel to the high resistance relay R. The relay R is at once released and unlocked, at the same time disconnecting the loud speaker 13 at its left-hand contact. At the front contact of the jack J a circuit is completed for the cut-off relay CO, which disconnects the line L from the trunk T and connects it to the jack J. The relay R, upon being released, remains 55 deenergized for the reason that it is de-

pendent upon its locking circuit and can only be re-actuated by closing the contact 15. The relay R operates to open the bridge circuit 17 of the loud speaker 13 before the cut-off relay CO connects the line L to the 70 jack J. Consequently, the loud speaker is disconnected before ringing current can be applied to the line.

If, while the line is being used for program transmission, the subscriber should desire to initiate a call he removes his receiver from the switchhook and closes a circuit from ground over the contact 14 to the conductor 20. This short-circuits the high resistance relay R, thereby deenergizing said relay and 75 at the same time reducing the resistance of the circuit through the line lamp 12 so that the latter now glows. The relay R, upon being released, is unlocked so that it cannot be again actuated except by closing the contact 15 and said relay disconnects the loud speaker from the line, as already described. The operator, upon observing the line lamp 12, inserts a plug in the jack J, thereby effacing the line lamp and actuating the 80 cut-off relay to disconnect the line L from the program trunk T and connect the line to the switching jack J.

While the circuit, as above illustrated, is especially applicable to private branch exchanges, it is equally applicable to ordinary telephone exchanges.

It will be obvious that the general principles herein disclosed may be embodied in many other organizations widely different 100 from those illustrated without departing from the spirit of the invention as defined in the following claims.

What is claimed is:

1. In a program system, a subscriber's 105 telephone line, means to connect said telephone line to a program station, switching terminals for said line, a line signal associated therewith, a low impedance program receiver for said line adapted to be bridged across the line, means to establish a circuit over the two sides of said line in parallel to operate said line signal, a relay controlling the connection of said program receiver to the line, and means to establish a circuit for 110 said relay over the two sides of the line in parallel.

2. In a program system, a subscriber's 115 telephone line, means to connect said telephone line to a program station, switching terminals for said line, a line signal associated therewith, a low impedance program receiver for said line adapted to be bridged across the line, means to establish a circuit over the two sides of said line in parallel to 120 operate said line signal, a relay controlling the connection of said program receiver to the line, and means to establish a circuit for said relay over the two sides of the line in 125 parallel, the resistance of said relay being 130

sufficiently high to prevent the operation of said line signal.

3. In a program system, a subscriber's telephone line, means to connect said telephone line to a program station, switching terminals for said line, a line signal associated therewith, a low impedance program receiver for said line adapted to be bridged across the line, means to establish a circuit over the two sides of said line in parallel to operate said line signal, a relay controlling the connection of said program receiver to the line, means to establish a circuit for said relay over the two sides of the line in parallel, the resistance of said relay being sufficiently high to prevent the operation of said line signal, means to lock up said relay when actuated by a subscriber, means for establishing a connection to the switching terminals at the central station, and means responsive to the establishment of such connection for releasing and locking said relay

and for thereafter disconnecting the line from the program station and connecting it to the switching terminals.

4. In a program system, a subscriber's telephone line, means to connect said line to a program station, switching terminals for said line, a line signal associated with said switching terminals, means for establishing a circuit to operate said line signal over the two sides of the line in parallel, a program receiver adapted to be associated with said line, means under the control of the subscriber to bridge said receiver across the line in series, and means responsive to the establishment of a connection to said switching terminals at the central office for opening said bridge and thereafter connecting said line to the switching terminals.

In testimony whereof, I have signed my name to this specification this 30th day of November, 1923.

JOHN F. TOOMEY.
